UNITED STATES PATENT OFFICE.

SAMUEL L. TRUEBLOOD, OF KENOVA, WEST VIRGINIA.

CAR-COUPING.

SPECIFICATION forming part of Letters Patent No. 722,192, dated March 3, 1903.

Application filed April 16, 1902. Serial No. 103,225. (No model.)

To all whom it may concern:

Be it known that I, SAMUEL L. TRUEBLOOD, a citizen of the United States, residing at Keno-
5 nova, in the county of Wayne and State of
West Virginia, have invented a new and useful
5 Car-Coupling, of which the following is a
specification.

The invention relates to improvements in
car-couplings.

10 The object of the present invention is to
improve the construction of car-couplings
and to provide a simple, inexpensive, and
efficient one of great strength and durability
adapted to couple automatically and capable
15 while in motion of being readily operated to
release the knuckle for uncoupling and to
open the knuckle to arrange the parts for
automatic coupling.

20 A further object of the invention is to pro-
vide a car-coupling of this character in which
the knuckle-locking mechanism will be posi-
tive and reliable in its operation in permitting
the arm of the knuckle to engage it automati-
25 cally and which will be positively retained
in engagement with the knuckle and effec-
tually prevented from being thrown out of
such engagement by jar and vibration.

20 The invention consists in the construction
and novel combination and arrangement of
30 parts hereinafter fully described, illustrated
in the accompanying drawings, and pointed
out in the claims hereto appended.

35 In the drawings, Figure 1 is a horizontal
sectional view of a car-coupling constructed
in accordance with this invention, the knuckle
being closed. Fig. 2 is a transverse sectional
view of the same. Fig. 3 is a detail perspective
40 view of the pivoted catch. Fig. 4 is a detail
view of a portion of the knuckle. Fig.
45 5 is a detail view illustrating the manner of
mounting the arm on the shaft or pintle of
the catch.

Like numerals of reference designate corre-
sponding parts in all the figures of the draw-
ings.

45 1 designates a draw-head provided at one
side with a guard-arm and having a knuckle
2, pivoted at the opposite side by means of a
knuckle-pin 3, arranged in suitable eyes of
50 the draw-head in the usual manner. The
knuckle 2 is provided with an arm 4, beveled
at its inner end and adapted, as hereinafter

explained, to engage a beveled end face 5 of
a pivoted catch 6, preferably formed integral
with a shaft or pintle 7; but it may be fixed to
the same in any other suitable manner. The
55 catch is provided with an inner shoulder 8,
which is arranged to engage the arm of the
knuckle to lock the latter in its closed posi-
tion. The shaft or pintle 7 is removably ar-
ranged in bearings 9 and 10, located at the
60 inner and outer walls of the recess or open-
ing of the draw-head. The inner bearing 10
consists of a socket to receive the inner end
of the shaft or pintle, and the outer bearing 65
9 is open at the outer side to permit the shaft
or pintle to be readily introduced into and
removed from its bearings. The shaft or
pintle is retained in its bearings by a vertical
70 pin 11, arranged in a suitable perforation of
the draw-head and located at the outer side
of the outer end of the shaft or pintle, as
clearly illustrated in Fig. 1 of the drawings.
The draw-head is provided with an approxi-
75 mately segmental recess 12 to permit the
catch to swing backward and forward to en-
gage and release the arm of the knuckle, and
the segmental recess 12 is offset from the
outer face of the knuckle to provide a wall
80 or shoulder 13, to be engaged by a latch 14,
hereinafter described. The latch 14, which
is mounted in a slot or bifurcation 15 of the
catch, consists of an upright portion and an
arm 16, arranged at an acute angle to the
85 upright body portion of the latch and dis-
posed at an inclination, as clearly shown in
Fig. 2, when the knuckle is closed and locked.
The outer edge of the latch conforms to the
configuration of the front or outer end face
90 of the catch, and it is adapted to fit flush
against the same when the latch is drawn in-
ward. The lower portion of the latch is pro-
vided with an inclined slot 17, through which
95 passes a pin 18, and which permits the latch
to be drawn inward to carry its upright body
portion out of engagement with the wall or
shoulder of the draw-head to permit the catch
to swing upward and backward. The arm 16
100 of the latch extends above the catch when
the latter is in engagement with the arm of
the knuckle, and the said arm 16 is connected
with a chain 19 or other suitable flexible con-
nection, which extends outward through an
opening 20 at one side of the draw-head and

which may be connected with any suitable operating mechanism. When the chain or other flexible connection is drawn outward, the latch is moved into the slot or bifurcation 5 of the catch, and the latter is partly rotated to swing it backward out of engagement with the arm of the knuckle. This operation may be readily performed while a car is in motion, and the knuckle will then be free to open. 10 This will enable cars to be readily shifted and handled in the usual manner in making up trains and distributing cars, and there will be no liability of a person being injured. 15 In order to obviate the necessity of going between cars and opening the knuckle, especially when it is discovered while a car is in motion that the knuckle is closed, the shaft or pintle 7 is provided with an arm 21, which is adapted when the chain is pulled outward 20 to the limit of its movement to kick the knuckle open and which is also adapted in coupling to be engaged by the arm of the knuckle to throw the catch forward into engagement with the arm of the knuckle when 25 the said catch is thrown backward beyond the center. Should the catch be at the forward limit of its movement and in the position shown in Fig. 2, the beveled portion of the arm of the knuckle will engage the bevelled front face of the catch and lift the same, and thereby couple automatically. The arm of the shaft or pintle might be rigid with or integral with the same; but in order to avoid recessing the draw-head to enable the arm to 30 swing the same distance as the catch the latter and the shaft or pintle are permitted a limited movement independent of the arm 21 to enable the latter to depend from the shaft or pintle at all times and to simply oscillate forward or outward from an approximately perpendicular position and backward to such position. The arm will extend forward or outward in position to be engaged by the knuckle when the catch is at 35 the limit of its rearward movement, and it will be arranged approximately in a depending vertical position when the catch is lifted out of engagement with the arm of the knuckle and swung backward slightly beyond the center, so that a further movement of the operating mechanism will carry the arm 21 outward and kick the knuckle open. This movement will also admit of the catch being swung backward out of engagement with the arm of 40 the knuckle without opening the latter, and the parts will remain in such position for automatic uncoupling and will permit the knuckle to open. This operation of the arm is accomplished by means of a slotted collar 45 or head 22, loosely arranged on the shaft or pintle adjacent to the front or outer end thereof and receiving a lug or projection 23, fixed to the shaft and arranged in the slot 24. The lug or projection may be fixed to the 50 shaft in any suitable manner, either by threading it into the same, as shown in Fig. 55, or by forming it integral with the shaft or

pintle. When the lug or projection is formed integral with the shaft or pintle, a suitable entrance-groove leading to the slot 24 will be 70 provided. The slot 24 extends around the top of the collar and terminates at opposite sides of the upper end of the body portion of the arm, and the lug or projection 23 is arranged at the front end of the slot when the 75 catch is in its engaging position. When the catch swings rearward out of engagement with the arm of the knuckle, the lug or projection during a portion of the movement travels in the slot. This movement carries 80 the lug or projection to the rear end of the slot and holds the arm rigid with the shaft or pintle to enable the latter to operate on the knuckle, as before described. The arm 21 is provided with a beveled face 25, arranged to 85 be engaged by the arm of the knuckle. In order to relieve the pintle 7 of strain, the draw-head is provided at the inner or rear side of the segmental recess 12 with a curved wall 26, extending downward to a point beyond the shoulder 13 and arranged to be engaged by the upper portion of the catch and forming a solid abutment for the same. This prevents the catch from being forced outward when the knuckle is locked and is subjected 90 to a strain, and the shaft or pintle will be thereby greatly relieved of strain. The curved wall 26 terminates short of the bottom of the draw-head to provide sufficient space to form a passage-way for the arm of the knuckle. 95 100

What I claim is—

1. In a car-coupling, the combination of a draw-head, a pivoted knuckle, a pivoted catch arranged to engage the arm of the knuckle to lock the latter in its closed position, and an arm connected with the pivot of the catch and actuated by and adapted to actuate the same and arranged to be engaged by the knuckle to throw the catch into its engaging position, said arm being also arranged to engage and open the knuckle, substantially as described. 105
2. In a car-coupling, the combination of a draw-head, a pivoted knuckle, a pivoted catch arranged to engage the knuckle, and an arm mounted on the pivot of the catch and arranged to be actuated by the same and adapted to actuate the said pivot and arranged to be engaged by the knuckle to throw the catch into engagement with the same, said arm being also arranged to engage and open the knuckle, substantially as described. 110
3. In a car-coupling, the combination of a draw-head, a pivoted knuckle, a pivoted catch arranged to engage the knuckle, and a swinging arm connected with the pivot of the catch and arranged to be engaged by the knuckle and also to engage the knuckle, said catch having a limited movement independently of the swinging arm, substantially as described. 115
4. In a car-coupling, the combination of a draw-head, a pivoted knuckle, a pivoted catch having a shaft or pintle provided with a lug or projection, and a swinging arm mounted 120

- on the shaft or pintle and provided with opposite shoulders to be engaged by the lug or projection, substantially as described.
5. In a car-coupling, the combination of a draw-head, a pivoted knuckle, a pivoted catch having a shaft or pintle, an arm having a slotted sleeve loosely arranged on the shaft or pintle, and a lug or projection carried by the shaft and arranged in the slot of the arm to limit the independent movement of the catch, substantially as described.
6. In a car-coupling, the combination of a draw-head, a pivoted knuckle, a swinging catch movable transversely of the draw-head and having a slot or bifurcation, a latch arranged within the slot or bifurcation and arranged to extend from the catch to engage the draw-head, and provided with a slot, a fastening device passing through the slot and securing the latch in the slot or bifurcation of the catch, and means connected directly to the latch for operating the same and the catch, substantially as described.
7. In a car-coupling, the combination of a draw-head, provided with a recess and having a shoulder at one end of the same, a pivoted knuckle, a swinging catch movable transversely of the draw-head and operating in the recess and arranged to engage the knuckle, and a slideable latch mounted on the catch and arranged to project normally beyond the same to engage the shoulder of the draw-head, and means connected directly to the latch for operating the catch and the latch, substantially as described.
8. In a car-coupling, the combination of a draw-head having a recess and provided adjacent to the same with bearings, one of the bearings being open, a pivoted knuckle, a pivoted catch provided with a shaft or pintle 40 detachably arranged in the said bearings, said catch being arranged to operate in the recess, a pin mounted on the draw-head at the open bearing and retaining the shaft or pintle in the same, a knuckle-engaging arm 45 carried by the shaft or pintle, and a latch mounted on the catch and arranged to engage the draw-head, substantially as described.
9. In a car-coupling, the combination of a draw-head having a segmental recess and 50 provided at one side of the same with a curved wall forming a solid abutment and terminating short of the bottom of the draw-head to afford a passage-way for the arm of a knuckle, said draw-head being also provided with 55 bearings, and a catch having a shaft or pintle arranged in the said bearings, said catch being also arranged adjacent to the said wall and abutting at its upper portion against the same when it is in engagement with the arm 60 of the knuckle, substantially as and for the purpose described.
- In testimony that I claim the foregoing as my own I have hereto affixed my signature in the presence of two witnesses.
